(57) **CLAIM**

The ornamental design for a data input device, as shown and described.

DESCRIPTION

FIG. 1 is a front bottom right perspective view of a data input device according to a representative embodiment of my new design;

FIG. 2 is a rear top left view of the data input device;

FIG. 3 is a rear bottom right view of the data input device;

FIG. 4 is a bottom view of the data input device;

FIG. 5 is a top view of the data input device;

FIG. 6 is a left side view of the data input device;

FIG. 7 is a right side view of the data input device;

FIG. 8 is a front view of the data input device; and,

FIG. 9 is a rear view of the data input device.

The broken lines shown as dashed lines depict portions of the data input device that form no part of the claimed design. The broken lines shown as dash-dot lines define boundaries of the claimed design and form no part thereof.
